UNITED STATES PATENT OFFICE.

SAMUEL D. MOTT, OF PASSAIC, NEW JERSEY, ASSIGNOR, BY MESNE ASSIGNMENTS, TO MOTORMOBILE COMPANY, OF JERSEY CITY, NEW JERSEY.

MUFFLER FOR AUTOMOBILES.

SPECIFICATION forming part of Letters Patent No. 683,860, dated October 1, 1901.

Application filed December 4, 1900. Serial No. 38,702. (No model.)

To all whom it may concern:

Be it known that I, SAMUEL D. MOTT, of Passaic, Passaic county, New Jersey, have invented certain new and useful Improvements 5 in Mufflers for Automobiles, of which the following is a full, clear, and exact description.

My invention relates to improvements in automobiles, and particularly to that class of automobiles in which a steam-engine is used 10 in connection with a fluid-consuming burner and a boiler and water-tank.

The object of my invention is to produce a vehicle of this class in which all the parts of the machine are easily accessible and in which 15 the arrangement is compact and durable, with the especial end in view of producing a machine which is reliable and which can be operated by a person not particularly skilled in engineering.

20 Further objects of my invention are to arrange the parts so that they can be very conveniently manipulated where manipulation is necessary and so that the parts necessary to be seen are reasonably conspicuous.

25 Still another object is to obviate the disagreeable puffing of the exhaust which is common to some vehicles of this class and to cause the exhaust to produce a mere dripping instead of a steam-jet.

30 With these ends in view my invention consists of an automobile the construction and organization of which will be hereinafter described and claimed.

Reference is to be had to the accompanying 35 drawings, forming part of this specification, in which similar figures of reference refer to similar parts throughout the several views.

Figure 1 is a sectional side elevation of an automobile embodying my invention. Fig. 40 2 is a broken perspective view of the assembled parts, the water-tank being shown in section. Fig. 3 is a broken elevation of the water-tank. Fig. 4 is a detail of the means for driving the forced circulation-shaft, and Fig. 45 5 is a broken detail perspective view of the water-tank and shows the compartments in the lower part thereof.

Obviously the style of vehicle can be departed from to any extent and the general 50 arrangement of the parts preserved. As illustrated, I have shown the mechanism of the

machine on a very common style of vehicle 13, and this carries the boiler 10, the engine 11, which is pivoted, as shown at 11^a, and the tank 12, the boiler and engine being beneath 55 the main seat and the tank beneath the rear seat, as shown clearly in Fig. 1. The boiler is cased in and has a reduced supplementary casing 14 and 15, provided with suitable doors, this part of the casing being intended to 60 inclose the burner, and it is made to extend below the vehicle - body, so as to be easily reached. The boiler 10 has issuing from it the steam-feed pipe 16, which supplies the engine 11, and the feed-pipe is provided with 65 a key valve or lock 17, which can be turned so as to shut off the steam and lock the valve and the key carried away, thus preventing the unauthorized use of the vehicle.

In connection with the vehicle I employ 70 many things common to automobiles of this class—as, for instance, the usual controlling-levers 19 and 20, the former connecting by means of the hollow shaft 21 and crank 22 with the main throttle-valve, while the lever 20 connects with the reversing-gear (not shown) by means of the rod 23 and the connecting-rod 24.

The engine has the ordinary exhaust-pipe 75 25, which, however, instead of delivering into the air or into a common form of muffler delivers into the muffling-chamber 26, which is a separate compartment below the water-holding portion of the tank 12, being separated from the tank proper by a horizontal 80 partition, as shown. From the muffling-chamber depend several drip-pipes 26^a, so that the exhaust-steam which enters the chamber will be condensed, particularly as the top 85 wall of the muffling-chamber is cooled by the water in the tank 12, and so the steam will be precipitated and the water will simply drip out through the drip-pipes 26^a. It will thus be seen that I provide means for muffling the sound of the exhaust and that I also precipitate steam, so that there is no visible exhaust. 90

I use this same muffling-chamber 26 for the safety-valve 27, so that in case the boiler blows off the same effect is had as when the engine exhausts, the safety-valve being connected by the pipe 28, connection 29, and pipes 30 and 31 with the throttle or feed pipe 95 100

16. At the end of the pipe 28 I locate an ordinary air-valve 32, so that before steam is gotten up air-pressure can, if desired, be pumped into the pipe 31 and connections to 5 be used in the burner to promote combustion until there is sufficient steam, the air in this case passing through the pipe 31 and mingling with the oil in the pipe 37, which will be presently referred to. Of course it will 10 be understood that the valve 32 can be located at any convenient point in the system where air-pressure will be communicated to the burner; but the place illustrated is very convenient. The pipe 31 conveys the steam 15 or air to the burner, and the pressure is controlled by an ordinary diaphragm 31^a, which is not shown in detail, but is regulated by a customary hand-screw 31^b. The diaphragm receives boiler-pressure through the pipe 40^c, 20 connecting with the pipe 40; but the connection may be with any part of the system where boiler-pressure can be obtained. An extension 30^a of the pipe 30 connects with a diaphragm 33, and leading from the other side 25 of the diaphragm is a pipe 34, which connects with a pressure-gage 35, this being preferably located on the dashboard, where it can be readily seen. The pressure-gage, the pipe 34, and the front side of the diaphragm-casing 33 are filled with some fluid which will 30 not readily freeze, preferably alcohol, so that pressure is communicated in the same way as if steam were let directly into the pressure-gage. This feature is not shown in detail, 35 as it is illustrated and described in another application of mine.

The fuel-supply, which is preferably oil, is taken from the reservoir 36, which is suspended below the front part of the vehicle-body, and, as illustrated, this reservoir is made almost wholly of glass, so that one can see just what the fuel-supply is; but obviously the same result can be had by making either the ends or the sides of glass. In my 45 automobile the fuel is drawn from the reservoir or tank by a burner analogous to an inspirator, and so it is possible to use a glass reservoir, as it is not necessary to have air or other pressure within. The fuel is taken 50 from the reservoir or tank 36 through a pipe 37, which is also provided with a branch pipe 38, both the main pipe and branch pipe being controlled by cocks, and the pipe 37 leads to the main burner of the boiler, while the pipe 55 38 leads to the pilot-burner. The steam-pipe 31 leads to the main burner, and this also has a branch pipe 39, controlled by a cock and leading to the pilot-burner. The steam is intended to mingle with the oil and atomize 60 and volatilize it, so as to produce a gaseous hydrocarbon capable of burning suitably in the burner.

The initial water-supply for the boiler is taken through a pipe 40, which is controlled 65 by a valve 41; but after the initial supply the water-supply of the boiler is kept up by a water-feed taken from the reservoir 42, the struc-

ture and arrangement of the reservoir and its boiler connections being described specifically in a separate application of mine filed 70 simultaneously with this.

The boiler has a forced circulation, the mechanism being turned by a shaft 43, and this is provided with a sprocket-wheel 44, which is loose on the shaft (see Fig. 4) and 75 which connects with the shaft 43 by means of the ratchet-wheel 45 on the shaft and the pawl 46 on the sprocket-wheel 44. The sprocket-wheel 44 is driven by a chain 47, connecting with the sprocket-wheel 48 on the 80 driving-shaft 49 of the engine. The object of the ratchet connection with the shaft 43 is to provide means for driving the forced circulation only when the vehicle is being moved forward, so that if the reversing-gear is applied the sprocket-wheel 44 will turn loosely 85 and the circulation will not be forced in the wrong direction. The water-supply pipe 40, referred to above, takes water from a separate compartment 40^a, arranged horizontally 90 in the lower part of the tank 12, just above the chamber 26, this compartment communicating with the main tank through a hole 40^b. (Shown in Fig. 5.) There is no means for circulating the water in the tank, and the arrangement just described prevents the whole body of water from being heated to any extent, as the heat from the exhaust or blow-off steam will be absorbed mostly by the water in the compartment 40^a. 95

The boiler is provided with a low-water indicator (not shown) which operates the shaft 50, this being mounted in suitable supports 51 and having at one end a crank 52, connected with the water-indicator, and at the other end a crank 53, which moves a connecting-rod 54, and the latter is pivoted in turn to the pointer or hand 55, which moves over the graduated scale 56, and so indicates the amount of water in the boiler. This indicator or scale 56 is located on the dashboard, so that it may always be seen by the driver. These dashboards on automobiles are often made of celluloid, and it is my intention to have the scale 46 cased in, but by a transparent casing which may be a film of celluloid, and as lanterns are used on the vehicle the driver can see through the transparent cover and notice the condition of water in the boiler either at night or in the daytime. 100

The vehicle has the customary steering-lever 58 and foot-brake lever 59, and I have also shown it with the ordinary driving-gear 60, connecting the driving-shaft 49 and the rear axle; but obviously these details may be 105 changed without affecting the principle of my invention.

Having thus described my invention, what I claim, and desire to secure by Letters Patent, is—

1. In an automobile, the water-tank having a plurality of horizontal compartments therein, the lower serving as a muffling-chamber for the exhaust and blow-off of the vehicle.

cle, and a second chamber or compartment serving as a supply for the water-feed, the said second chamber having connection with the body of the tank.

5 2. In an automobile, the water-tank having a muffling-chamber in the bottom and a water-compartment above and next to the muffling-chamber, said water-compartment being in communication with the body of the 10 tank.

3. In a steam-propelled motor-vehicle, the combination with the boiler and engine, of a water-tank having two compartments in the lower part thereof, one containing water and

communicating with the water-holding portion of the tank, and the other serving as a muffling-chamber and having drip-openings therein, a feed-water pipe communicating between the tank and boiler, and the blow-off and exhaust pipes discharging into the muffling-chamber.

In testimony whereof I have signed my name to this specification in the presence of two subscribing witnesses.

SAMUEL D. MOTTO.
